UNITED STATES PATENT OFFICE.

EDWARD R. IVES, OF BRIDGEPORT, CONNECTICUT.

DESIGN FOR A TOY GUN-STOCK.

SPECIFICATION forming part of Design No. 27,808, dated November 2, 1897.

Application filed June 15, 1897. Serial No. 640,921. Term of patent 3½ years.

To all whom it may concern:

Be it known that I, EDWARD R. IVES, a citizen of the United States, and a resident of Bridgeport, in the county of Fairfield and State of Connecticut, have invented a certain new and useful Design for Toy Gun-Stocks, of which the following is a specification, reference being had to the accompanying drawing, showing a part thereof.

10 The figure shows a perspective view of a toy gun-stock, illustrating my design.

The leading feature of my design resides in a toy gun-stock, the same comprising the shape and configuration shown in the accompanying drawing of a butt-and-barrel portion,

15 the edges of which are square, and an enlargement upon said barrel having a groove formed in the top near the side thereof, as shown.

In the drawing, 1 indicates the butt-end of 20 the stock, which is of substantially the usual contour, having an enlarged end and provided with square edges, as shown. 2 represents

the barrel-like extension, which is also provided with similar square edges and a groove 3 in the top surface thereof. The stock is further provided with an orifice 4, which extends therethrough.

The barrel 1 is provided with an enlargement 5, which covers the end and returns upon the under side, as at 6, for a short distance. Said enlargement is further extended in a vertical plane and is provided upon its near side with a vertical recess 7, as shown.

What I claim is—

The design for a toy gun-stock, substantially as herein shown and described.

Signed at Bridgeport, in the county of Fairfield and State of Connecticut, this 8th day of March, A. D. 1897.

EDWARD R. IVES.
